ABSTRACT OF THE DISCLOSURE

An orbiting polygonal array of rollers carries a moving textile web as it rotates in a liquid dye-filled pressurized cylindrical chamber. The chamber is lined with axial corrugations, in one embodiment, so that the rollers move alternately close to the near point and then the far point of the corrugations which creates dynamically variant pressure zones of alternatively high and low pressures in the region of the roller, resulting in the dye being forced alternately through the web in accordance with the pressure variation.

BACKGROUND OF THE INVENTION

This invention is in the field of textile processing and particularly relates to wet processing equipment wherein it is desired to wash or dye the textile web or otherwise thoroughly expose the textile web fibers to a liquid bath. The invention concerns a device incorporating a means for flexing a spread out, open-width textile web as it flows through a liquid bath. In particular the invention concerns an improvement which causes the liquid to be circulated under high pressure through the flexed web in alternating directions and at a high cyclical rate.

In prior art devices of this type a moving web is threaded in a liquid bath around a polygonal array of rollers, which preferably have helical faces. In consequence of the rotation of the array, the web is rapidly oscillated in the liquid. At the same time, the rotation of the rollers by reason of their frictional engagement with the web causes a series of moving corrugations as the web is pulled into contact with the helices which form the face of the rolls. These corrugations cause a twisting and untwisting of the individual fibers as the array turns, facilitating complete exposure of the web to the liquid bath while the oscillating movement effects a scrubbing, forcing the liquid between the strands and fibers. This concept is shown in U.S. Pat. No. 3,136,146 and a variation is shown in U.S. Pat. No. 3,321,939.

In some wet processes and in the case of some particularly dense or heavy textile webs the above apparatus will not sufficiently expose the fibers to the bath. This is especially, but not exclusively, true in dying where it is desired to achieve complete saturation and uniform exposure. The basic apparatus described by the prior art forces liquid through the web primarily in one direction. By means of the present invention, however, liquid is forced through the web in both directions and in addition at a considerably higher cyclical rate and higher pressure than is possible with the basic apparatus. Thus the liquid is driven into the intermost fibrils of the web to a greater extent than is possible by the prior art apparatus. By this means very dense or tightly woven webs and webs composed of the finest fibrils and most densely woven

2

yarns can be completely saturated and uniformly exposed to the liquid medium to a degree and extent not possible in the past.

SUMMARY OF THE INVENTION

5 A pressurized liquid-filled cylindrical chamber has a radially varying inner surface constituting, in a preferred embodiment, axial corrugations of preselected depth and number. Positioned inside the chamber is a concentrically orbiting polygonal array of rollers preferably having helical faces. The moving textile web enters the chamber and is wound around the polygonally arranged rollers to describe a polygon having its radial extremities at the rolls. As the array rotates the rollers orbit within the chamber 10 so that the space between a roller and the interior of the chamber varies as the radius of the chamber varies. This produces a high pressure in the liquid as the roll approaches and passes a high spot (radially closer to the center) in the corrugation and a low pressure as the roll 15 rotates away from a low area (radially further from the center) in the corrugation. In its tendency to equalize pressure, the fluid flows through the web in alternating 20 directions.

BRIEF DESCRIPTION OF THE DRAWINGS

25 FIG. 1 shows diagrammatic elevation view of the apparatus as a dyeing bath in a range with two washers. FIG. 2 shows a partially diagrammatic and sectional elevation view of the apparatus. 30 FIG. 3 shows a perspective view of the rotating array. FIG. 4 shows diagrammatically a series of possible configurations for the chamber inner surface.

DESCRIPTION OF THE PREFERRED EMBODIMENT

35 FIG. 1 shows a range of textile processing machines for dyeing chosen by way of example to illustrate a typical installation of the present invention. Neither the machines in the range nor the specific construction or the 40 usage of the invention for dyeing should be taken as limiting the utility of the invention since it is susceptible of a wide range of form and utility. The high pressure fiber flexing device 1 of the invention is ranged in line with a washer 2 and a rinser 4. The textile web 6 originates 45 on a roll 8 and is transmitted via guide rolls 10 and 12 into the washer 2. Upon exiting the washer 2, the web 6 passes between squeeze rolls 14 and 16 and is guided by a guide roll 18 into the rinser 4. The web 6 upon exiting the rinser 4 passes through a second set of squeeze rolls 50 20 and 22 to remove the rinse liquid. The web 6 then passes over an entry roll 24 and into the high pressure fiber flexing device 1 containing a dyeing bath. Upon exiting the fiber flexing device 1, the web 6 flows between two squeeze rolls 26 and 28 and then on to a dryer (not shown).

55 The washer 2 and the rinser 4 may be of the conventional type, such as a stack of alternating reversing rolls, may utilize the basic fiber flexing device of the patents hereinbefore cited or, may utilize the apparatus of the present invention.

60 FIG. 2 illustrates the details of the high pressure fiber flexing device 1. The rectangular column 30 for entry and exit of the moving web has a separator 32 mounted in it

which is secured along the ends of the column 30. The column sides 34 and 36, which are plates somewhat wider than the textile web, have splash pans 38 and 40 on their upper ends and are attached at their lower ends to a cylindrical pressure chamber 42. The circular cross section of the chamber 42 has been modified somewhat by installation of a slotted channel 44 at the point of connection of the column 30 in order to facilitate installation of an entry guide roll 46 and exit guide roll 48 as well as for mounting the column 30.

Inside the chamber is mounted a polygonal array of five orbiting rollers 49, 50, 51, 52 and 53. The details of the polygonal array are shown in FIG. 3 where an array of three orbiting rollers 55, 56 and 57 is mounted on two rotatable plates 58-58, each fixed to a transverse axle 59. Faces 60 of the rollers 55, 56 and 57 are formed as a double oppositely directed helix outrunning from the center of each roll. It is evident that the number of rollers in the array may vary within the concept of the invention, thus FIG. 2 shows a five-roller array while FIG. 3 shows a three-roller array. The operation and construction of the array is more fully disclosed in my patents numbered 3,136,416 and 3,321,939 as cited above.

Referring to FIG. 2, the polygonal array is rotatably mounted on end walls 62-62 of the pressure chamber 42, the transverse axle 59 being connected to a drive means (not shown) to rotate the array within the chamber. As in the machine described in Patent 3,321,030, the rollers may be independently power driven so that they will not drag upon initial contact with the web. However, it is not considered necessary in this embodiment of the invention to drive the rollers since they are nearly always in contact with the moving web 6 and therefore have a constant surface speed equal to that of the web 6.

The inner surface of the pressure chamber 42 comprises a circumferential series of corrugations having high points 64 and low points 66, high being here defined as radially closer to the center of the chamber and low as radially further from the center of the chamber. The corrugations extend axially between the ends 62-62 of the pressure chamber 42.

The web 6 is threaded down the column 30 past the entry guide roll 46, around the rollers 49, 50, 51, 52 and 53 past the exit guide roll 48 and finally up the column 30. The web 6 flows in the counterclockwise direction around the array. The array rotates in the clockwise direction as shown by the arrow 70. The separator 32 prevents splashing of the liquid in the column 30.

The pressure chamber is filled with a dye liquor, a prevailing pressure being established by filling the column to the desired height. For example, a ten foot column of dye liquor would give a prevailing pressure of 4.33 pounds per square inch at the bottom of the chamber 42.

As a rotating roller approaches a high point 64 on the corrugated surface the dye-liquor filled space therebetween rapidly decreases from a maximum to a minimum, the resulting high pressure forcing the liquid out of the space. This pressure forces liquid through the web between the helices of the roller in the area near the high point of the corrugation.

As a roller passes from proximity to a high point, 64 with its relatively confined space to proximity to a low point 66 with its larger space, a concomitant decrease in pressure occurs causing liquid to flow in the opposite direction through the web into the low pressure cavity formed by the low point 66.

It is apparent that faces of the rollers may take a variety of forms other than the helices described herein the only requirement being that the dye liquid be able to flow through the web.

As a preferred structure, the inner surface may be a lining which is removable from the structure in order to facilitate maintenance as well as to substitute a different lining. The lining may also be flexible or resilient so that

extreme pressures would cause flexing rather than excess pressure through the web or vibrations in the apparatus.

FIGS. 4A through 4D show by way of example a series of alternative configurations for the inner surface of the chamber 42. By choosing an appropriate configuration the pressure level and the duration of flow in each direction can be controlled.

For example, FIG. 4A shows a corrugation in which the high points are sharply peaked and the low points sloping. This means that the duration of the high pressure zone as a roller passes by will be shorter than that of the adjoining low pressure zone. As a result, since basic laws require that the same volume of liquid flow in each direction, the pressure change in the high pressure zone will be of greater magnitude than the pressure change in the low pressure zone with respect to the prevailing pressure within the chamber.

The configuration of FIG. 4B shows an exaggerated version of the same relative relationship, in which the low pressure zone will be of much longer duration than the high pressure zone. Of course, there are practical limits to the pressure change differential. If the ratio of the zone duration is too great the excess liquid will be forced out of zone boundaries other than through the textile web. The configurations of FIGS. 4C and 4D will provide substantially equal zone durations at maximum pressures, however, the time rate of change of pressure will be less in configuration 4D than in configuration 4C due to the relatively gentle slope of the wall connecting the high point 64 and the low point 66 in configuration D.

By utilizing the variables described above, liquid flow characteristics in each direction can be varied or adjusted to suit particular requirements. Of course, other variables are present in the apparatus and the ultimate performance of any particular version depends on all the variables. Such factors as orbit velocity, roller diameter, proximity of the roller to the inner surface of the chamber, fluid side losses, and viscosity are some of the more apparent variables.

The corrugations shown in the preferred embodiment extend axially across the cylinder, however, it is seen that the corrugations could be arranged in a helix, herringbone or other shape as they traverse the cylinder.

It is therefore intended that the embodiments herein described are by way of example and are in no way limiting to the broad scope of the invention claimed.

I claim:

1. A textile web-finishing apparatus comprising; a chamber having inlet and exit means for a textile web; and adapted to support a textile web within the chamber an array of polygonally arranged orbiting rollers whose faces are formed as an oppositely directed helix outrunning from the center of each roll; said chamber having a radially variant inner surface surrounding the array to form varying sized zones between the rotating rollers and the inner surface of the chamber as the rolls pass therearound.

2. The apparatus of claim 1 wherein said inner surface comprises corrugations having high points radially closer to the array and low points radially further from the array adapted to form in the liquid medium attending high and lower pressure zones adjacent to each roller of the array.

3. The apparatus of claim 1 further comprising means to contain a liquid medium at a predetermined prevailing pressure within the chamber.

4. The apparatus of claim 1 wherein said inner surface is a removable lining within the chamber.

5. The apparatus of claim 1 wherein the inner surface is resilient.

6. The apparatus of claim 3 wherein said containing means comprises a column of preselected height openly communicating with the chamber at said inlet and exit

means, said column adapted to contain the liquid medium to a height selected for establishing the prevailing pressure and further adapted for entry and exit of a textile web.
